Design for stove plates
Fig 3
Des 881

Des. 881

A. C. Barstow, of Providence, R. I.
Letters Patent No. 881. Dated April 14th 1857.

The schedule referred to in these Letters Patent, and making part of the same.

Des. 881

To all persons to whom these Presents shall come:

Be it known that I, A. C. Barstow, of Providence in the County of Providence and State of Rhode Island, have produced a new and original design for the top and bottom plates of a Parlor Stove, and I hereby declare that the said new design is fully described and represented in the following specification and accompanying drawings to which reference is hereinafter made.

The figures of the accompanying plates of drawings represent my new design.

In plate 1, Fig: 1, is a plan or top view of the top plate.

In plate 2, Fig: 2, is a plan or top view of the bottom plate.

In plate 3, Fig: 3, is a longitudinal central vertical section of the top plate, and

Fig: 4, a similar view of the bottom plate.

The top plate is ornamented with mouldings a, a, &c, of the shape shown in fig. 1, plate 1, and fig. 3, plate 3, the raised diamond figures b, b, &c, the raised triangular figures c, c, &c, and the circular figures d, d, &c, composed of rays.

The bottom plate is ornamented with mouldings e, e, &c, as shown in fig. 2, plate 2, and fig. 4, plate 3, and the raised triangular figures c, c, &c.

Having thus described my new design, I shall state my claims as follows.

What I claim as my invention and desire to have secured to me by Letters Patent, is the new design for stove plates consisting of the mouldings and ornamental raised figures as herein above described and represented in the drawings.
